UNITED STATES PATENT OFFICE.

WILLIAM J. GRINDE, OF BROOKLYN, NEW YORK.

METAL BARREL.

1,195,462.

Specification of Letters Patent. Patented Aug. 22, 1916.

Application filed November 20, 1915. Serial No. 62,572.

To all whom it may concern:

Be it known that I, WILLIAM J. GRINDE, a citizen of the United States of America, and residing in the borough of Brooklyn, 5 in the county of Kings and State of New York, have invented a certain new and Improved Metal Barrel, of which the following is a specification.

My invention relates to metal barrels and 10 particularly to the end closures therefor, the object of my invention being to provide a readily applied rigid end closure for a metal barrel.

In the accompanying drawing, Figure 1 15 is a vertical section through a barrel in which my invention is illustratively embodied; Fig. 2 is a horizontal section therethrough; Fig. 3 is a detached broken perspective of portion of the barrel; and Fig. 20 4 is a broken perspective of a detail.

In the form here shown, the present barrel is of the knock-down type and comprises two sheet metal sections 10 and 11, each curved to semi-cylindrical shape and having 25 its longitudinal margins outwardly recurved to form in the assembled barrel oppositely-faced flanges 12 and 13 exterior to the barrel at the joint 14 between the body sections. A key 15, also formed from sheet metal, has 30 recurved marginal flanges 16 and 17 which enter the grooves formed by the flanges 12 and 13 and rigidly tie the barrel sections together throughout the length of the body of the barrel. Adjacent each end of the barrel 35 the sections 10 and 11 are peripherally grooved in register at 18 and 19 to afford substantially flat internal ledges or seats for the respective end closures 20 and 21. As shown, these end closures comprise wooden 40 heads 20 and 21 which rest upon the said ledges and are of a thickness substantially corresponding to the portions 22, 23, of the barrel body which extend beyond the grooves 18 and 19. To firmly secure these heads to 45 their seats, I employ for each a split, channel-section, locking ring 24, the flange 25 of which in assembled position overlies the outer margin of the closure head while the inner flange 26 enters the groove 18 or 19

formed in the body of the barrel. After 50 the locking ring has been adjusted in position as shown in Fig. 1, it is fastened by means of nails driven through perforations 27 and 28, adjacent the ends of the split ring. These nails pierce the portions 22 55 and 23 of the barrel body and enter the wooden closure heads 20 and 21 substantially at right-angles to the axis of the barrel, thus holding the channel ring in position and thereby securely fastening the heads. 60 While this assembly of parts is very rigid, the barrel may be still further reinforced by making the end flanges 27 and 28 of the keys 15 of such length that they may be extended beyond the ends of the barrel 65 and bent over and secured to the heads 20 and 21 by means of nails driven through the flanges. This gives a more or less rough finish however, and it is preferable to make the flanges 27 and 28 shorter and insert 70 them in the grooves 18 and 19 where they are concealed and protected.

The structure not only affords a very strong barrel which will contain heavy substances, such as cement, without breakage, 75 even on rough handling, but it also presents the great advantage that it may be shipped in knock-down form with the barrel sections 10 and 11 nested and the remaining parts of the barrel stacked. This is not only true of 80 the original shipment to the user of the barrel, but it also applies to a return shipment of the barrel after use, since the only parts apt to be injured on the opening of the barrel are the heads 20 or the locking rings 24 85 and keys 15 and these may be readily replaced.

Various modifications in detail of construction will readily occur to those skilled in the art without departing from what I 90 claim as my invention, and I do not limit myself to the precise form shown.

I claim as my invention:—

A sheet metal barrel having its wall inwardly grooved adjacent the end of the barrel to form a substantially flat internal ledge, a wooden head resting upon said ledge and an external split locking ring of chan-

nel section having a pair of uninterrupted annular flanges one flange overlying the outer face of the head and its other flange entering said peripheral groove, together with means piercing said ring and entering the wooden head for securing said locking ring in position to retain said head.

In testimony whereof I have signed my name to this specification, in the presence of two subscribing witnesses.

WILLIAM J. GRINDEN.
